(57) **CLAIM**

The ornamental design for a door trim for an automobile as shown and described.

DESCRIPTION

FIG. 1 is a first side perspective view of a door trim for an automobile in accordance with my new design;

FIG. 2 is a second side perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a right side elevational view thereof; and,

FIG. 8 is a left side elevational view thereof.

The broken lines and the half-tone gray area within the broken lines shown in FIGS. 1-8 represent the environmental structure and form no part of the claimed design.

A second embodiment of my new design includes the mirror image of the door trim shown in FIGS. 1-8.
